UNITED STATES PATENT OFFICE.

ROBERT QUIGLEY AND JAMES CUNNINGHAM, OF PORTAGE, PENNSYLVANIA.

AUTOMATIC MINE-SHAFT GATE.

Application filed August 21, 1922. Serial No. 583,294.

To all whom it may concern:

Be it known that we, ROBERT QUIGLEY and JAMES CUNNINGHAM, citizens of the United States, residing at Portage, in the county of Cambria and State of Pennsylvania, have invented certain new and useful Improvements in Automatic Mine-Shaft Gates, of which the following is a specification.

10 This invention relates to mine-shaft gates, and more specifically, to an improved electro-mechanical gate-operating mechanism.

One object of the invention is to provide 15 an improved means whereby the mine-cage automatically controls a switch in the electric circuit that supplies power for opening and closing the gate.

Another object is to provide an improved 20 current-reversing switch for controlling reversal of the motor that forms part of the mechanism for opening and closing the gate.

Another object is to provide an improved 25 mechanism whereby the gate operates a double-pole switch that controls the motor-current.

Another object is to provide a device of 30 this character with a simple and effective means for retarding action of the reversing switch for a limited period after the cage has operated its controlling means.

With the foregoing and other objects in view, the invention consists in the construction and arrangement of parts such as described hereinafter in connection with the accompanying drawings. In these drawings, in which similar reference characters correspond to similar parts throughout the several views,

40 Figure 1 is an elevation representing a landing-place of a mine-shaft, a gate at the entrance of the shaft, and my improved gate-operating mechanism.

Figure 2 is a horizontal view of the device partly in section,

45 Figure 3 is an enlarged detail view of a part of the cage-controlled mechanism and the reversing switch that it controls.

Figure 4 is a diagrammatic view of the 50 motor and its electric circuit.

Referring to these drawings in connection with the above mentioned reference characters, the cage-landing is represented by the portion of the horizontal line at 5, and the 55 gate 6 being provided with uprights 7 and wheels 8, the latter being mounted to roll

on a track 9. Springs 10 are provided at each end of the track to cushion the shock of the gate at each end of its path of travel. A rack 11 is secured to the gate by any appropriate means, and meshes with a pinion 12 on the driving shaft 13 of a transmission gear member which includes a gear-wheel 14. The latter meshes with a pinion 15 on the driving shaft of an electric motor 16 which is in circuit with any appropriate source of electromotive force through the medium of an arrangement of conductors and switches that will presently be described. The motor 16 is preferably 3-phase alternating current, and two of its terminals are directly connected to conducting wires 17 and 18 which are, in turn, connected to the intermediate binding posts of a double-throw double pole switch that is generally designated by the numeral 19. A switch member 20 (Fig. 1) is hinged or pivoted to these intermediate binding posts, and is provided with a depending arm 21 by which it is operatively connected to a shifting or reversing device that is operable by means on or carried by the rack 11. This reversing device comprises a bar 22 pivotally mounted on two levers 23 and 24 disposed substantially in the vertical plane of the rack 11 and slightly spaced above the latter. The rack 11 is provided with an abutment or pusher 25 that moves against the lower end of the lever 24 and shifts it from its vertical position to a leftwardly inclined position, and this shifts the bar 22 leftward, and in doing so, one of its pins 26 rocks the switch 20 and disconnects it from the contacts 27 while moving it into connection with contacts 28. The purpose of this switch will presently appear.

The contacts 28 are connected respectively to conducting wires 29 and 30 which have their other ends connected to a pair of springs or contact members preferably such as shown at 31 in Fig. 3, and indicated diagrammatically in Fig. 4. The contacts 27, of the switch 19, are connected to conducting wires 33 and 34 which are connected to contacts 35 and 36 (Fig. 4), similar to the one shown in Fig. 3, and two more of such contacts, shown at 37 and 38, Fig. 4, are in connection with the feed-wires or conductors 39 and 40 which are connected or connectable with an electric generator of any appropriate kind.

Referring now to Fig. 2, in which 41

designates the mine-cage, and to Fig. 3; it will be seen that a roller 42 is carried by a portion 43 of the cage. A bow-spring 44 is secured on the framing 45 of the elevator-shaft in position to press a rod or plunger 46 which is slidable through the member 45 and is pressed outward by a spring 47 against the spring 44. A rotary switch member is indicated at 48 and is provided with two pairs of contacts or bridges for connecting the contacts 31, 35, 36, 37 and 38 in a manner presently described. These bridges are indicated at 49, 50, 51 and 52 (Figs. 2 and 3). The rotor or switch-member 48 is mounted on a shaft and shifted in one direction by the rod 46, a jointed link 54 and an arm 55, the latter being secured to the shaft 53 and pivoted to the link 54. Any appropriate guiding support, not shown, may be provided for the link 54. The rotary switch 48 is shifted in the opposite direction by means of a weighted arm or lever 56, and a dash-pot is indicated at 57 for retarding the lever 56 in shifting the switch 48.

A spring or compressible pusher 58 is mounted on the rack 11, and its free end coacts with a shoulder 59, on the lower end of the lever 23, for returning the switch 20 to its normal position (shown in Fig. 1) when the gate closes, through the medium of the bar 22, as will presently appear.

The operation of the device is as follows:

When the cage 41 approaches the landing-place 5, its roller 42 presses the bow-spring 44 so as to push the rod 46 rightward (Fig. 3) and permit the weighted lever 56 to descend and turn the rotary switch 48, this brings the contacts 49 and 50 out of engagement with the fingers or contacts 31, 37 and 38 (the normal position shown in Fig. 3), and brings the contacts 51 and 52 into engagement with the fingers 35, 36, 37 and 38. The circuit is now closed between the motor 16 and the generator-conductors 39 and 40 and starts the motor to running in the direction for opening the gate. This is done through the medium of the gearing which includes the rack 11, pinion 12 and gear-wheels 14 and 15. When the gate approaches its open position, the lug or pusher 25 presses the lever 24 and shifts it so as to move the switch-member 20 out of engagement with the contacts 27 and into engagement with the contacts 28, thereby breaking the circuit, and the circuit stays broken so long as the cage remains at this landing and depresses the springs 44 and 47; but as soon as the cage releases these springs, the spring 47 shifts the rod 46 to its normal position shown in Fig. 3, so that the contacts 49 and 50 are again engaged by the contacts 31, 37 and 38, thereby not only closing the circuit, but also reversing it, so that the motor 16 now runs in the direction for closing the

gate. As the gate closes, its spring 58 engages the lug or shoulder 59 and thereby shifts the lever 23 so as to move the switch-member 20 to its normal position shown in Fig. 1, and in this position the circuit is broken, because the switch member 20 is now out of circuit with the contacts 31, and the motor remains inoperative until the switch 48 is again operated by the cage and its connections. As the lever 23 moves to its normal inclined position shown in Fig. 1, its shoulder 60 depresses the spring 58 and releases it from the shoulder 59 so that the closing of the gate is not hindered by the spring 58.

From the foregoing, it will be seen that, though the switch 16 is in a sense a "reversing switch," its operation, as such, is dependent on the switch 19, and vice versa.

It is not intended to limit this invention to the exact details of construction and arrangement as shown and described, but changes may be made within the scope of the inventive ideas as claimed.

We claim:

1. An automatic gate operating mechanism for mine shafts comprising a motor for moving said gate; a switch for alternately reversing the direction of current supplied to said motor; and a second switch for alternately connecting said motor with currents of proper direction to reverse the direction of its rotation.
2. An automatic gate operating mechanism for mine shafts, comprising a motor for moving said gate; a motor circuit; a switch in said circuit for reversing the direction of current flow therein; and a gate actuated selecting switch also in said circuit adapted to alternately supply currents of different direction from said reversing switch to said motor, to change the direction of rotation of the latter, said selecting switch being shiftable at substantially the end of each gate movement, and prior to actuation of said reversing switch.
3. An automatic gate operating mechanism for mine shafts comprising a motor for moving said gate; a reversing switch controlled by the cage in said shaft for controlling the direction of rotation of said motor; and a two way switch controlled by said gate interposed between said reversing switch and motor, adapted to alternately break the circuit from said reversing switch for operating said motor in one direction, and to make the circuit from said reversing switch preparatory to operating said motor in the other direction.
4. An automatic gate operating mechanism for mine shafts comprising a motor for moving said gate; a motor circuit; a reversing switch in said motor circuit, controlled by the cage in said shaft; a two way switch in circuit with said reversing switch

adapted to alternately break the circuits from said reversing switch to said motor; and a gate carried trip for actuating said two way switch.

- 5 5. The combination of a shaft, a cage to travel up and down therein, a gate to close an entrance to the shaft, a rack on the gate, an electric motor, transmission gearing operatively connecting the motor to the rack
- 10 so that when the motor travels in opposite directions it opens and closes the gate, a reversing switch included in the circuit with the motor, an actuating device constantly

tending to reverse the said switch, spring-pressed means to hold said switch in its normal position, means operable by said cage for depressing the spring-pressed means and permitting said switch to be reversed, a double-throw switch in circuit with said motor, and means controllable by the gate for breaking the circuit during closing and opening movements of the gate.

In testimony whereof, we affix our signatures.

ROBERT QUIGLEY.
JAMES CUNNINGHAM.
